US00D896270S

(12) **United States Design Patent** (10) Patent No.: **US D896,270 S**
(45) Date of Patent: **** Sep. 15, 2020**

(54) **DISPLAY PANEL OR PORTION THEREOF
WITH A GRAPHICAL USER INTERFACE**

(71) Applicant: **MAGIC LEAP, INC.**, Plantation, FL (US)

(72) Inventors: **Tim Zurmoehle**, Fort Lauderdale, FL (US); **Andrea Isabel Montoya**, Plantation, FL (US); **William Adams**, New York, NY (US); **Gregory Minh Tran**, Miami, FL (US); **Lorena Pazmino**, Wilton Manors, FL (US); **Robert John Cummings MacDonald**, White Rock (CA); **James M. Powderly**, Fort Lauderdale, FL (US)

(73) Assignee: **Magic Leap, Inc.**, Plantation, FL (US)

(**) Term: **15 Years**

(21) Appl. No.: **29/724,774**

(22) Filed: **Feb. 19, 2020**

Related U.S. Application Data

(63) Continuation of application No. 29/640,871, filed on Mar. 16, 2018, now Pat. No. Des. 879,138.

(51) **LOC (12) Cl.** **14-04**

CLAIM

The ornamental design for a display panel or portion thereof with a graphical user interface, as shown and described.

DESCRIPTION

The sole FIGURE is a front view of a display panel or portion thereof with a graphical user interface showing our design.

The outermost broken line rectangle illustrates a display panel or portion thereof that forms no part of the claimed design.

1 Claim, 1 Drawing Sheet
